M. TURNER.

LADY'S COSTUME.

No. 15,504.

Patented Oct. 28, 1884

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,504, dated October 28, 1884.

Application filed August 7, 1884. Term of patent 3½ years.

To all whom it may concern:

Be it known that I, MARY TURNER, of the city, county, and State of New York, have invented and produced a new and original Design for a Pattern of a Lady's Costume, (numbered 9,343;) and I do hereby declare that the engraved prints accompanying this specification convey to any one accustomed to using paper patterns a clear understanding of how a garment made up by the pattern will appear.

The design shows a round walking-skirt and a basque. The skirt exhibits a plaited panel at the right side crossed by two straps, a deep front drapery extending from the panel to the left side, exhibiting draping plaits in its back edges and flaring forward below the plaits in its left back edge, a deep full back drapery displaying plaits in its front edges, and loop-

ings at the center. The basque exhibits 20 closely-fitted fronts that outline a point at the lower end of the closing, curve high over the hips, and display a plaited Pompadour ornament below the neck, a deep closely-fitted back that exhibits its skirt arranged in two 25 deep loops below the waist-line, a standing collar, and coat-sleeves that round upward toward the outside seams.

What I claim as my invention, and desire to secure by Letters Patent, is—

The design for a lady's costume, as shown in the engraved prints accompanying this specification.

MARY TURNER.
